METHOD AND APPARATUS FOR THE CONTINUOUS SPINNING OF ARTIFICIAL SILK

Erich Sellner, Wuppertal-Barmen, Germany, assignor to American Bemberg Corporation, New York, N. Y., a corporation of Delaware

Application July 18, 1940, Serial No. 346,202
In Germany July 19, 1939

4 Claims. (Cl. 18—8)

This invention relates to improvements in methods for the continuous spinning of artificial silk threads.

It is an object of the invention to provide a method and an arrangement of apparatus for practising said method both being adapted to permit the spinning, liquid treatment and winding of a plurality of individual artificial silk threads at the same time on the same machine.

More especially the invention contemplates the provision of means for conducting a plurality of simultaneously, freshly produced threads over a system of skewed rollers of which the rollers rotate in the same direction so that the threads are caused to travel or wander laterally in spiral or helical fashion from one end of the roller system to the other, all of the several individual threads performing the same spiral or helical lateral wandering simultaneously, means being provided for keeping the threads separated from each other during said wandering and means also being provided for chemically treating and washing said threads while they are passing in lateral wandering fashion over said roller system.

In the prior art, proposals have already been made for the continuous so-called "wet spinning" method of producing artificial threads from solutions of cellulose and derivatives thereof as such as esters and ethers, such methods consisting in passing a plurality of freshly spun threads in spiral or helical fashion over one or more pairs of skewed rollers, that is, rollers rotating in the same direction but whereof the axes intersect or cross, the threads being subjected to liquid treatment while passing over the roller system. These threads are obtained simultaneously from a number of spinning nozzles, preferably adjacently situated, and they pass together over the same rollers in screw-thread like looped fashion, thus permitting the output of a plurality of spinning nozzles to be chemically treated and washed at the same time.

It has however been found that in attempting to conduct a plurality of threads (coming from a number of different spinning nozzles or funnels) in parallel and helical fashion over the pair of rollers, various difficulties are frequently encountered in that the various convolutions corresponding to the individual threads coming from the spinning funnels tend to run together or even overlap, hence causing the threads to become tangled. Furthermore, even when the machine is being strung up and the individual threads are being started on the forwarding and

take-up devices, it is often very difficult to keep them apart.

In accordance with the present invention, these difficulties are obviated by means of the auxiliary arrangements herein described, the same being explained in detail in conjunction with the accompanying drawing.

In the drawing, Fig. 1 shows a view of an illustrative embodiment of an apparatus adapted for practising the method of the invention and illustrating the spinning nozzles, the roller system, liquid treating means and the take-up devices. Fig. 2 is a side view of the roller system.

The artificial silk threads produced for example from cuprammonium cellulose solution (although the method is applicable also to other varieties of artificial silk) are obtained from a suitable number of spinning nozzles or funnels, say three, for example. In the drawing, the spinning funnels are indicated by 1, 1', 1'' and the artificial threads issuing therefrom by 2, 2', 2'', the said funnels being distributed longitudinally of the machine and disposed directly adjacent each other. The threads are conducted over the common guide bar 3 and passed over the common and positively driven guide roller 4 whereupon they pass to the pair of skewed rollers 5, 6 over which they pass in the form of parallel, separate helical windings, after which they run over the idler guide rollers 7 and 8 to the three separate winding devices consisting of positively driven spools 9, 9' and 9''; the windings as they are shown passing over the rollers 5, 6 being illustrated as considerably spread apart for the sake of clarity in illustration.

The freshly spun artificial silk threads may be treated with spinning acid or cupric ammonium sulphate solution as they pass in one or more convolutions over the positively driven roller 4, such treatment being effected during travel upon the roller surface. Suitable liquid delivering means of known type, e. g. applicators, sprays, pipes, valves, cocks and the like (not shown) may be used for this purpose, a trough 12 being provided to catch the excess liquid. The final removal of copper or other salts and the final washing is accomplished in the usual manner while the threads are present upon the pair of skewed rollers, suitable liquid delivering or applying means of known type being likewise provided at this point, as diagrammatically indicated by the cock 13.

The roller 7, which is preferably an idler roller, is provided with three parallel grooves corresponding to the three artificial silk threads and

this roller may be kept moistened with brightening liquid for the purpose of brightening the thread. The threads thus thoroughly purified and preliminarily prepared then pass over the guide roller 8 to the reels, from the cores of which they may subsequently be removed in the form of compact wound structures which are then dried after the fashion of spin cakes whereby they are allowed to shrink freely.

In stringing up the machine for operation, the following procedure is followed:

One of the threads, e. g. 2, coming from the funnel 1, is first passed over the guide bar 3 and roller 4 and conducted to the pair of skewed rollers 5, 6 around which pair of rollers the thread is draped or looped in helical form; the thread is caused by rotation of the rollers 5, 6 to wind up in screw thread like or helical fashion and to face toward the free end of the pair of rollers. Before this can occur, however, a bar 10, running substantially parallel to one of the skewed rollers is positioned in such a manner that the thread convolutions on one side of the pair of skewed rollers will be pressed slightly inwardly out of the tangential direction. While the first helix (that of thread 2) is being formed upon the pair of rollers (or after it has been completely formed) the second thread 2' is applied in similar helical fashion around the pair of rollers and the helical turns formed are similarly pressed inwardly and are displaced even more out of the tangential direction by a bar 11 as depicted in Fig. 2. This bar is positioned below the bar 10 and is similarly substantially parallel to one of the pair of rollers. While the second helix (that of thread 2') is being formed along the pair of rollers (or after it has been completely formed) the third thread 2'' is passed in helical fashion around the pair of rollers so that it will wind and travel up on said pair of rollers in free and unhindered fashion, i. e., without being pressed inwardly out of the tangential direction by either the bar 10 or the bar 11. The threads reaching the upper end of the skewed pair of rollers are taken off in order, individually passed over the guide rollers 7 and 8 and wound up on their respective reels.

The invention therefore provides a reliable means for simplifying and cheapening spinning machines and especially for utilizing the relatively expensive skewed rollers in multiple fashion as by running two, three, or even four separate threads in parallel through said machine. By this arrangement and means the various threads may with safety be caused to travel in parallel relation to each other with a separation of only a few millimeters between them and thus control their passage over the rollers in order to insure uniformity of treatment thereof. The passage control and guiding of the threads is so reliable and uniform that the spun products obtained possess uniform physical properties.

What I claim is:

1. The method of simultaneously spinning, from a cellulosic solution, a plurality of individual rayon threads comprising: spinning at least two separate threads from a conventional spinning solution, progressively conveying one of said freshly spun threads around a pair of spaced, co-motive rotating surfaces as a traveling open helix having a pitch equal to several times the diameter of said thread, progressively conveying the other freshly spun thread around same pair of rotating surfaces as a traveling open helix of substantially identical pitch and extent interwound with said first helix in non-contact therewith,

simultaneously applying a treating fluid to corresponding, substantially equal interwound portions of each of said helixed threads as moved along said spaced rotating surfaces, and individually unwinding the threads from said spaced rotating surfaces after said liquid treatment while maintaining said non-contacting relationship therewith.

2. An apparatus for simultaneously spinning, from a cellulosic solution, a plurality of individual rayon threads comprising: a pair of rollers arranged side-by-side in spaced relation, means for driving said rollers to rotate at corresponding peripheral speeds, means for spinning at least two separate threads from a conventional spinning solution, means for progressively directing one of said freshly spun threads around and along said pair of rotated rollers as a traveling open helix having a pitch equal to several times the diameter of said thread and for progressively directing the other freshly spun thread to the same pair of rotated rollers as a traveling open helix of substantially identical pitch and extent interwound with said first helix in non-contact therewith, means for applying a treating fluid to corresponding substantially equal interwound portions of each of said helixed threads as moved along said rotating rollers, and thread take-up means for each of said threads operative to maintain non-contact of said treated threads as progressively removed from said rollers.

3. An apparatus for simultaneously spinning, from a cellulosic solution, a plurality of individual rayon threads comprising: a pair of cylindrical rollers arranged side-by-side in spaced skewed relation, means for driving said cylindrical rollers to rotate at substantially identical peripheral speeds, means for spinning at least two separate threads from a conventional spinning solution, means for progressively directing one of said freshly spun threads around and along said pair of rotated rollers as a traveling open helix having a pitch equal to several times the diameter of said thread and for progressively directing the other freshly spun thread to the same pair of rotated rollers as a traveling open helix of substantially identical pitch and extent interwound with said first helix in non-contact therewith, said thread-directing means including a bar disposed in a plane substantially tangent to one of said paired rollers and adapted for association with said helices such as to displace the thread sections thereof passing through said plane alternately inward and alternately outward with respect thereto, means for applying a treating liquid to corresponding substantially equal interwound portions of each of said helixed threads as moved along said rotating rollers, and thread-reeling means for each of said threads operative to maintain non-contact of said treated threads as progressively removed from said rollers.

4. An apparatus for simultaneously spinning, from a cellulosic solution, a plurality of individual rayon threads comprising: a pair of cylindrical rollers arranged side-by-side in spaced skewed relation, means for driving said cylindrical rollers to rotate at substantially identical peripheral speeds, means for spinning at least two separate threads from a conventional spinning solution, means for progressively directing one of said freshly spun threads around and along said pair of rotated rollers as a traveling open helix having a pitch equal to several times the diameter of said thread and for progressively directing the other freshly spun thread to the same

pair of rotated rollers as a traveling open helix of substantially identical pitch and extent interwound with said first helix in non-contact therewith, said thread-directing means including a pair of parallel spaced bars disposed in a plane substantially tangent to one of said paired rollers and adapted for sequentially-varied displacing association with the bar-traversing thread sec-

5 tions, means for applying a treating liquid to corresponding substantially equal interwound portions of each of said helixed threads as moved along said rotating rollers, and thread-reeling means for each of said threads operative to maintain non-contact of said treated threads as progressively removed from said rollers.
